VALVE MECHANISM FOR INTERNAL-COMBUSTION ENGINES.

1,150,751.

Specification of Letters Patent. Patented Aug. 17, 1915.

Application filed April 24, 1914. Serial No. 834,121.

To all whom it may concern:

Be it known that I, ADAM ECKERT, a citizen of the United States, and a resident of Perth Amboy, in the county of Middlesex and State of New Jersey, have invented a new and Improved Valve Mechanism for Internal-Combustion Engines, of which the following is a full, clear, and exact description.

10 This invention relates to an improved valve mechanism for motors and more particularly to a valve mechanism for internal combustion engines adapted for controlling the supply or inlet of gases to the combustion chamber which are exploded upon being compressed therein during the reciprocation of the piston or otherwise, as well as the exhaust of the spent gases after the explosion has taken place, as for instance, in 15 the common 4-cycle engine.

20 A further object of the invention is the provision of an improved valve mechanism in which cylindrical valve chambers or casings are provided adjacent to the inlet and 25 exhaust ports to snugly and movably receive piston valves therein, while novel means are provided for adjusting the valves for controlling the time at which gas is admitted to the combustion chamber and the quantity 30 of fuel supplied.

With the above and other objects in view, the invention resides in the peculiar combination and arrangement of parts to be hereinafter more fully described, illustrated 35 and claimed, it being also an object to provide a device which is simple in construction, durable and efficient in operation and not likely to get out of working order.

Reference is to be had to the accompanying drawings forming a part of this specification, in which similar characters of reference indicate corresponding parts in both views and in which—

40 Figure 1 is a vertical sectional view through an internal combustion engine provided with my improved valve mechanism; and Fig. 2 is a horizontal sectional view on the line 2—2 of Fig. 1.

45 In illustrating the application of my improved valve mechanism an internal combustion engine is shown, although the device may be adapted for any other type of engine or motor, and in the drawings the numeral 10 discloses the engine cylinder which is 50 preferably provided with a surrounding water jacket 11 having continuous communica-

cation at the top and bottom as distinguished from two points at diametrically opposite points and at which points cylinder valve casings or chambers 12 are provided. 60 The water jacket is located at the upper part of the cylinder and the lower part is flanged as shown at 13 for attachment to the usual crank case, there being the usual piston 14 moving or reciprocating in the cylinder and 65 connected by a pitman rod 15 with the crank shaft in the usual manner. A spark plug 16 is engaged in the head of the cylinder for ignition of the compressed combustible gases in the usual manner. 70

75 The valve casings 12 are formed integral with or otherwise carried by the cylinder in such a manner as to intercept the water jacket, and as shown, are provided with removable heads 13 bolted or otherwise secured to the casings proper. The inlet port is indicated by the numeral 17 and the exhaust port by the numeral 18, the same being located at diametrically opposite sides of the cylinder and communicating with the 80 interior of the valve casings 12. Mounted in each valve casing is a cylinder or piston valve 19, the same snugly fitting the casings and having reduced end portions 20. Any suitable means for lubricating these valves 85 may be employed.

90 The supply pipe is indicated by the numeral 21 and the exhaust pipe by the numeral 22, such pipes communicating with the valve casings at the inlet and outlet sides of the cylinder respectively. As a means for adjusting one or both of the valves to regulate the time at which the gas is admitted to the cylinder, the quantity of 95 gas admitted and the exhaust of the spent gases, the valves are connected by adjustable stems 23 with connecting rods 24 each having a sleeve 25 engaged on an eccentric 26 of a countershaft 27 suitably driven, as from a crank shaft although any other means for reciprocating the valves may be employed. This is believed sufficient for adjustment of the exhaust valve but the intake valve is provided at its reduced ends with counterbores, 100 the upper counterbore 28 being square to receive the squared end 29 of a combined guide and adjusting lever 30 which is frictionally held supported or suspended in the head 13 of the casing as by means of washers 31.

105 A handle or operating device 32 is provided for rotating the guide and lever as 110

well as to adjust the valve on the threaded portion 20 of the rod 23, it being understood that the valve at its lower end is provided with an interiorly threaded counterbore or socket 33 for receiving the threaded end of the rod. Thus, by rotating the guide and lever 30 the valve will be rotated on the rod 23 to adjust it vertically with respect to the inlet port to vary the sizes thereof for the time at which the port will be opened or closed and for admitting fuel and cutting off the supply of the same to the combustion chamber. The guide and lever 30 may be adjusted vertically to accord with the adjustment of the valve to permit the desired reciprocation of the latter, it being understood that while said device permits the valve to be rotated and adjusted in the manner described, the valve is permitted to slide or reciprocate independently of any movement of the guide during the operation of the engine. The said stems or rods 23 operate through guides 34 preferably projecting from a casting integral with the cylinder so as to guide the valves in a direct line during the reciprocation.

In the operation of an engine provided with my improved valve mechanism as described, when gas or a combustible mixture is supplied through the inlet pipe 21 and the valves are in the position shown in Fig. 1, gas is admitted through the inlet port 17 to the combustion chamber when the exhaust valve is closing the exhaust port 18. On the compression stroke such gases are compressed and the valve 19 is reciprocated to close the port 17. Such gases are then ignited and the impact of the explosion reciprocates the piston, and on the return stroke thereof the exhaust port is opened while the inlet port is still closed and the exhaust gases pass out through the exhaust pipe 22, communication in each case being established through the valve casing 12, so that upon the exhaust port being again closed and the inlet port opened, upon the opposite stroke of the piston gas is again supplied to the combustion chamber and this operation is continued. The inlet valve is timed to properly open and close the inlet port 17 for the purpose of admitting gas through the intake or manifold 21 into the cylinder and by turning the lever 32 the valve may be rotated on its stem and adjusted longitudinally with respect thereto and the valve casing, in such a manner as to control the extent to which the valve passes over the inlet opening on the compression stroke of the engine and thus serve to time the period of supply of gas to the cylinder on the recession of the valve. The exhaust valve is similarly constructed with the exception of the adjustment feature at the top, but such adjustment may be provided in connection with this valve to regu-

late the exhaust and timing thereof if desired.

It will be observed that the valves intercept the water jacket so that communication around the same is established at the top and near the bottom of the jacket, and the valves being close fitting will positively avoid the objection of the explosions taking place, particularly in the valve chambers or casings which results in deposits of carbon such as to interfere with the operation of the valves. In the present instance the valves snugly fit the interior surfaces of the casings and with the exception of the openings through the shell of the cylinder there are no possible avenues of escape to permit the explosions to take place, particularly in the valve casing. As the reciprocation of the valves can be regulated to a minimum the effect of the explosions on the valves will be unobjectionable.

In order to simultaneously adapt the valve casings or chambers 12 and the reciprocatory valve 19 therein as air compressors, each casing is provided with an inlet valve 35 through which air is drawn on the up strokes of the valves 19, and upon the return or down strokes of these valves air is compressed in the casings. During the compression action the valves 35 are closed and the air will escape through outlet valves 36 and is conveyed by a suitable conduit 37 to the carburetor which communicates with the manifold 21 or directly to the manifold, the essential idea being that it is connected with the fuel supply to thin out and carbonize the same and thus produce a better mixture.

Having thus described my invention, what I claim as new and desire to secure by Letters Patent is:—

1. A valve mechanism for internal combustion engines, embodying a cylindrical casing, a valve operating in the casing and conforming in cross section thereto, a valve stem adjustably connected with the valve, means for reciprocating the valve and external means for adjusting the valve on the stem.

2. The combination with an engine cylinder having an inlet port and an exhaust port; of casings adjacent to said ports which are thus brought in connection with the cylinder, valves movable in the casings, means for moving the valves and having adjustable connections therewith, and exteriorly operated means for shifting one of the valves on its adjusting means.

3. In a valve mechanism for internal combustion engines, the combination with a cylinder having a piston reciprocating therein and valve casings having ports communicating with the combustion chamber of the cylinder; of cylindrical valves operable in the casings and having reduced extremities, an inlet pipe for one casing, an exhaust pipe for

the other casing, guide extensions projecting from the cylinder beneath the casings, and valve stems suitably operated for reciprocation through the guides and adjustably connected to the valves.

4. In a valve mechanism for internal combustion engines, the combination with a cylinder having a piston reciprocating therein and valve casings having ports communicating with the combustion chamber of the cylinder; of heads for said casings, cylindrical valves snugly fitting in the casings, valve rods connected to the valves, means for reciprocating the rods and valves carried thereby, one of said valves having a threaded socket in one end adjustably engaged by its respective rod and having a squared socket in its opposite end, and a guide and lever frictionally supported in the casing head and having a squared portion engaging the squared socket to permit movement of the valve independent of the guide and lever, rotation of said guide and lever oper-

ating to turn the valve to adjust it longitudinally with respect to its port.

5. A valve mechanism, comprising a cylindrical casing, a cylindrical valve in the casing and adapted for rotation therein, a valve stem suitably guided, said valve having reduced end portions with a threaded socket in one end and a squared socket in the other end, said valve stem being engaged in the threaded socket, an adjusting member having a squared portion engaging the other socket to permit reciprocation of the valve thereon, and a guide adapted upon being rotated to longitudinally adjust the valve in its casing.

In testimony whereof I have signed my name to this specification in the presence of two subscribing witnesses.

ADAM ECKERT.
